MICHAEL J. HANLON, OF WEEHAWKEN, NEW JERSEY, ASSIGNOR TO BLACK DIAMOND STEAMSHIP CORPORATION, OF NEW YORK, N. Y., A CORPORATION OF DELAWARE

METHOD OF REMODELING THE STERN STRUCTURE OF SHIPS

Application filed July 13, 1931. Serial No. 550,549.

This invention has general reference to naval architecture and/or marine engineering, and has more particular reference to an improved stern structure for ships and a method of remodeling or modifying that class of ships known as the "Hog Island Type A", the broad object in view being to effect a substantial increase in the speed of these vessels without materially altering the power plant capacity or increasing the fuel consumption.

This class of ships has been open to numerous objections, notably, their lack of speed, which may be mainly attributed to the peculiar construction of the stern portion of the hull which in addition to offering an unusually high resistance or drag, has caused a suction disturbance or turbulence adjacent the propeller, resulting in a reduction of the propulsion efficiency. The type of rudder employed on these ships also offers a further resistance to the forward motion of the ship and renders the steering and maneuvering of the ship difficult while subjecting the rudder and steering gear to undue strains, frequently resulting in fracturing or other damage to the rudders and steering gear.

These and other disadvantageous features have combined to render this type or class of craft inefficient and, hence, unprofitable to operate in their original condition, and, hence, the present invention comprehends an improved stern structure and a method of correcting the existing defects at a minimum expenditure of time, labor and material.

With the above recited and other objects in view, the invention resides in an improved stern structure and a method of remodeling or modifying ships of this class, which method is clearly set forth in the following description and illustrated in the accompanying drawings, in which several alternative structures and methods are set forth, while the claims cover the actual scope of the invention.

In the drawings:

Figure 1 is a fragmentary side view of the stern portion of a ship of the type specified, illustrating the same modified or remodeled in accordance with the present invention.

Figure 2 is a similar view of this type of ship as originally constructed.

Figure 3 is an enlarged fragmentary longitudinal sectional view illustrating the modified or remodeled construction.

Figure 4 is a horizontal sectional view taken approximately on the line indicated at 4-4 in Figure 1.

Figure 5 is a horizontal sectional view through the improved rudder, taken approximately on the line indicated at 5-5 in Figure 1.

Figure 6 is a vertical fragmentary sectional view taken approximately on the line 6-6 of Figure 1, and illustrating the connection between the rudder and rudder post.

Figure 7 is a horizontal sectional view taken approximately on the line 7-7 of Figure 1, and illustrating the modified contour of the stern frame above the propeller.

Figure 8 is a similar view taken approximately on the line 8-8 of Figure 1, illustrating the modified contour of the stern frame below the propeller.

Figure 9 is a fragmentary longitudinal sectional view of the modified stern frame, illustrating an alternative method of accomplishing the remodeling.

Figure 10 is a fragmentary horizontal sectional view taken approximately on the line 10-10 of Figure 9.

Figure 11 is a transverse diagrammatic horizontal sectional view taken approximately on the line indicated at 11-11 in Figure 3.

Figure 12 is a fragmentary side view of a further modification.

Figure 13 is an enlarged horizontal sectional view taken approximately on the line 13-13 of Figure 12.

Figure 14 is a similar horizontal section taken approximately on the line 14-14 of Figure 12.

In order to illustrate the type of ship to which the present method applies, Figure 2 discloses what is known as the "Hog Island Type A" class of ship, in which the stern portion A of the hull structure B is provided with a depending rudder stock supporting member C, the forward face D of which is

blunt or rounded and merges into a propeller accommodating arch E which merges into the rear or following stern portion F which is also blunt or rounded. The propeller G located immediately aft of the stern frame line F on the type of stern construction illustrated, has been found to lack propulsion efficiency, due to the suction disturbance or turbulence created by the suction or drag resulting from the blunt or rounded stern line F, in addition to the turbulence created by the forward face D of the depending portion or horn C, as well as the disturbance caused by the blunt leading edge H of the rudder I. In addition to this, the edge F caused a drag or suction while the face D of the horn C and the forward edge of the rudder H offered a considerable resistance.

In order to overcome or correct the deficiencies above noted whereby to obtain an increased speed without increasing the power plant or fuel consumption, the following method of remodeling or modifying the vessel has been devised, and said method consists in first cutting off or removing the depending or horn portion C of the stern frame approximately along the broken line J illustrated in Figure 2. The steel casting 15 or its equivalent is fitted inside the hull and extends horizontally and at a tangent to the remaining portion of the arch E. The steel casting 15 may be provided with arms 16 extending over a large area of the shell plating to provide an effective method of fastening and also to strengthen the hull at this point whereby to eliminate trouble which has existed due to excessive straining and vibration. The casting 15 has attached thereto the plating 17 which is also riveted or otherwise secured as at 18 to the stern portion A to provide an efficient streamline configuration and improve the speed length ratio of the hull at this point. The casting is also formed with an upstanding internal tubular boss 19 having an internal bushing 20 to provide a bearing of ample proportions which is suitable for the increased diameter of a new rudder post or shaft 21. The ordinary form of rudder indicated at I is discarded and a new design of streamline spade form rudder 22 will be fitted to the rudder post, as illustrated in Figure 3. The rudder 22 includes a rudder stock 23 extending the full length or height of the rudder and formed with curved arms 24, to which a steel shell 25 is suitably secured to define a cross sectionally horizontal streamline configuration, the rudder stock being disposed approximately one-third of the breadth of the rudder measured from its forward or leading edge 26. The method further consists in fitting and securing a streamline shell 27 in the propeller arch above the propeller and a streamline shell construction 28 to the hull below the propeller to produce efficient flow conditions

forwardly of the propeller. The shells or forms 27 and 28 as illustrated provide rearwardly converging outer surfaces which make for a minimum of suction disturbance as the hull moves through the water and which further function to improve the speed length ratio of the hull at these points. The method further consists in increasing the efficiency of the propeller G by substituting a new tail-shaft 29 of greater length, so as to relocate the propeller rearwardly in a position removed as much as possible from the area influenced by hull suction disturbance. This position will be as close as possible to the forward or leading edge of the new rudder 26 and at a point approximating the locus of intersection of the after end of the waterplane lines on a horizontal section through the center of the propeller shaft. This will locate the driving faces of the propeller blades as close as possible to the forward edge of the rudder, which is highly desirable in that the propeller slip will be decreased to increase the propulsive efficiency. It will also be found that the jet or wake of the propeller will be intersected by the rudder and deprived of its rotary motion and will thus be constrained to move away from the propeller in approximately a straight direction with very little rotary motion in the propeller jet. This will result in a reactive thrust on the propeller blades which becomes a component of and increases the total propeller thrust, resulting in an increase in speed with a minimum consumption of power and fuel. In order to strengthen and support the outboard portion of the new tail-shaft 29, a stern tube and outboard bearing 30 will be designed with an extension 31 equal in length to the increased length of the tail-shaft. An inboard bearing 32 will also be fitted and installed adjacent the inner or forward end of the tail-shaft and will carry the usual stuffing box. By following this method, it will be found that the alteration or modification to the vessel may be accomplished at a minimum expense of time, labor and material.

An alternative of certain of the steps of the previously described method is illustrated in Figures 9 and 10, in which instance the existing inefficient stern frame construction including the depending portion or horn C, the arch E and stern frame F are removed in their entirety and in lieu thereof, there is fitted and installed a new cast steel stern frame 33 which is fashioned as at 34 to produce the streamline effect obtained by the streamline shell 27, and which includes the horizontal portion 35 carrying the tubular boss 36 which serves as the rudder port or shaft bearing.

In the modification of the invention illustrated in Figures 12, 13, and 14, the old stern structure illustrated in dot and dash lines is replaced by a completely new stern structure 130

which is worked into the old structure, and in which the lower rear portion thereof is moved aft and shaped as shown to provide streamline exterior portions 40 and 41 above and below the propeller axis, a skag or shoe 5 extending rearwardly from the bottom of the portion 41 while stationary, and streamline rudder nose 43 is secured to and extends vertically from the rear of the skag or shoe and joins the re-modeled upper portion of the hull. A streamline rudder blade 45 is attached to a rudder stock 46 which is journaled in bearings 47 formed on the stationary rudder nose 43. A rudder post is secured to the rudder blade, as at 49, for controlling the movement of the rudder through the medium of a steering gear not shown.

The propeller 50 is re-located rearwardly in the propeller opening 51 defined between the skag 42, the portions 40, 41, and 44, of the hull and the rudder nose 43. The propeller hub cap 52 is substantially frustoconical and tapers rearwardly and extends into close proximity to the nose 43 of the rudder, the said nose being formed with a substantially conical rearwardly tapering boss 53 disposed in axial alignment with the hub cap. The forward end of the boss 53 and the rear end of the propeller hub cap are of substantially the same diameter, and this coupled with their close proximity, makes the boss in effect serve as a continuation of the hub cap and functions to reduce the suction disturbance of the propeller hub and hub cap.

In this construction, as in those previously described, the propeller is located at the locus or intersection of the water plane lines and at the point of least disturbance where the propeller blades work in solid water, thereby eliminating propeller slip and obtaining a maximum of propulsion efficiency.

While there have been illustrated and described several improved structures and methods of remodeling or modifying a vessel of the type specified, it is to be understood that other variations and modifications which fall within the scope of the claims may be resorted to when desired.

What is claimed is:

1. A method of modifying a ship of the type specified in order to decrease the hull resistance and improve the propeller propulsion efficiency consisting in removing the depending rudder post supporting portion of the stern frame, substituting for the old rudder a new spade type rudder of streamline horizontal cross section, relocating the propeller rearwardly, adding material to the stern frame above and below and in advance of the relocated propeller to provide a streamline following edge for reducing the suction disturbance and drag and for improving the speed length ratio of the hull.

2. A method of modifying a ship of the type specified in order to decrease the hull

resistance consisting in removing the depending rudder supporting portion of the stern frame, substituting a streamline spade rudder for the old rudder and adding material to the stern frame above and below the propeller to provide convergent surfaces for decreasing the drag or suction disturbance to a minimum.

3. A method of modifying a ship of the type specified as and for the purpose set forth consisting in removing the depending rudder supporting portion of the stern frame, fitting within the hull portion above the removed depending portion of the stern frame, a casting having a rudder post bearing of increased proportions, substituting for the old rudder a streamline spade rudder having a rudder post of increased diameter, adding a streamline shell material to the aft portion of the hull above and around said casting and adding material to the stern frame above and below the propeller to provide convergent surfaces for decreasing the drag or suction disturbance to a minimum.

4. A method of modifying a ship of the type specified as and for the purpose set forth consisting in removing the depending rudder supporting portion of the stern frame, fitting within the hull portion above the removed depending portion of the stern frame, a casting having a rudder post bearing of increased proportions, substituting for the old rudder a streamline spade rudder having a rudder post of increased diameter, adding a streamline shell material to the after portion of the hull above and around said casting, relocating the propeller aft at a point closely adjacent the entering edge of the rudder and adding material to the stern frame above and below the propeller to provide convergent surfaces for decreasing the drag or suction disturbance to a minimum.

5. A method of remodeling a ship of the class specified as and for the purpose set forth including the steps of removing the depending rudder portion of the stern frame, fitting and securing to the stern in the propeller arch above the propeller and below the propeller, streamline shells for reducing the drag and producing efficient flow conditions forward of the propeller.

6. A method of remodeling a ship of the class specified as and for the purpose set forth including the steps of removing the depending rudder portion of the stern frame, fitting and securing to the stern in the propeller arch above the propeller and below the propeller, streamline shells for reducing the drag and producing efficient flow conditions forward of the propeller and relocating the propeller rearwardly at the point of minimum suction disturbance.

7. A method of remodeling a ship having a propeller and a blunt round stern portion immediately in front of the propeller consisting

in moving the propeller rearwardly to the point of minimum suction disturbance and in applying streamline shell plates to said blunt stern properly proportioned to substantially
5 destroy the drag caused by said blunt stern and the turbulence of the water adjacent the propeller.

8. A method of remodeling a ship having a propeller and a blunt round stern portion immediately in front of the propeller consisting in moving the propeller rearwardly to the point of minimum suction disturbance and in reconstructing said blunt stern to lengthen the same and present streamline sides converging at a point immediately in front of
10 the propeller.

9. A method of remodeling the stern structure of a ship of the class described including the step of removing the depending portion
20 of the stern frame, altering the portion thereabove to increase the size of the rudder post bearing and substituting for the old rudder a new rudder of horizontal cross sectional streamline configuration having a rudder post of increased diameter.

10. A method of remodeling the stern structure of a ship of the class described including the step of removing the depending portion of the stern frame, altering the portion thereabove to increase the size of the rudder post bearing and substituting for the old rudder a new rudder of horizontal cross sectional streamline configuration having a rudder post of increased diameter and having its axis disposed approximately one-third
30 of the rudder breadth from the forward edge.
